CLAIM

The ornamental design for a table pedestal, as shown and described.

DESCRIPTION

FIG. 1 is a front elevational view of a table pedestal showing my design, wherein the phantom line showing forms no part of said design, the rear elevational view being a mirror image of the front view.

FIG. 2 is a right side elevation a view of the table pedestal, the left side view being a mirror image thereof.

FIG. 3 is a top elevational view of the table pedestal, the bottom view being a mirror image thereof; and,

FIG. 4 is a perspective view thereof.
